UNITED STATES PATENT OFFICE.

SYDNEY L. KAUFMAN, OF KITTANNING, PENNSYLVANIA.

TYPE-BAR ACTION.

1,267,873.

Specification of Letters Patent. Patented May 28, 1918.

Application filed November 18, 1914. Serial No. 872,765.

To all whom it may concern:

Be it known that I, SYDNEY L. KAUFMAN, a citizen of the United States, residing at Kittanning, in the county of Armstrong and 5 State of Pennsylvania, have invented a new and useful Improvement in Type-Bar Actions, of which improvement the following is a specification.

My invention relates to improvements in 10 devices for operating the type bars of type-writing machines.

The object of my invention is to produce a device adapted to accelerate or quicken the movement of the type bars toward the 15 platen at the finish of their stroke and a corresponding quick reverse movement away from the platen.

I accomplish this by means of the device 20 which consists of a self-contained flexuring bell crank pivotally connected intermediate the type bar and the key lever, and herein-after more specifically described, reference being had to the accompanying drawings forming part thereof, in which—

25 Figure 1 is a diagrammatic view of the platen, type bar and key lever with connecting mechanism.

Fig. 2 is an enlarged detail of a modified form of the accelerating mechanism.

30 Fig. 3 is a front elevation of one end of the plate which supports the forked brackets within which the bell crank levers 7 are pivotally mounted.

Fig. 4 is a top plan view of an end portion 35 of the said plate, showing the manner of securing the forked brackets thereto.

Referring to said drawings, 1 is the platen, 2 is the type bar and 3 is the key lever, the inner end of said type bar having a down-

40 wardly projecting member α to which is connected one end of the connecting rod 4, the rear end of said rod being connected to the upper end of the link 5, the rear end of which is pivotally connected to the member

45 6 of the bell crank 7, which is pivotally mounted on the post 8 secured in the frame of the machine. The said link 5 is also pivotally connected about midway its length to the link 9 which is pivotally connected to

50 the upper inwardly projecting end of the bell crank 10. The said bell crank 10 is pivotally connected at the junction of its members with the outer end of the crank 7 and at its lower end to the key lever 3 as

55 shown in the drawings. The mechanism

described comprises what I term a self-contained flexuring bell crank. The link 9 and upper end of the bell crank lever 10 provide what may be termed a toggle joint between the forward end of the bell crank 60 lever 7 and the pivotal connection between the link 5 and the link 9. When the key lever 3 is depressed, the members of the toggle connection are swung out of alinement and into an angular relation, as indicated 65 by dotted lines on Fig. 1, thereby gradually moving the pivotal connection at the lower end of the link 5 toward the pivotal connection between the link 9 and the bell crank lever 10. The link 9 which pulls 70 upon the link 5 thus has its leverage gradually decreased, with a corresponding increase in movement, resulting in imparting an accelerated motion to the type bar 2 on the stroke thereof.

75 Figs. 3 and 4 illustrate the supporting means for the various bell crank levers 7 when a number of the units are assembled in a typewriting machine. The vertically disposed plate 22 extends transversely across the key levers 3 at an intermediate point in the length thereof, said plate having the usual curved upper edge 22^a. A series of forwardly projecting forked brackets 23 are secured to the plate 22 adjacent the curved 80 upper edge 22^a thereof by suitable fastening members, such as the screws 24. The pivot pins 8 upon which the bell crank levers 7 are mounted connect the arms of the respective forked brackets 23. This supporting 85 means enables the necessary number of individual type bar actions to be compactly assembled into a typewriter basket without difficulty.

In Fig. 2 I show a modified form of the 95 accelerating mechanism which comprises the bell crank 11, in all respects similar to crank 10, connected to bell crank 12 which is similar to bell crank 7. A link 13 similar to link 9 is connected to one end of the 100 connecting rod 4 and the opposite end to crank 11 and a link 14 which is connected to said link 13 midway its length and to the bell crank 12. It is noted that the bell cranks 7 and 12 are provided with a recess 105 β which permits the inwardly projecting member of the cranks 10 and 11 and their connecting links to swing downwardly therein at the finish of the stroke.

Having described my invention what 110

I claim and desire to secure by Letters Patent is:

1. In mechanism for operating the type bar of a typewriting machine, the combination with a type bar, type bar connecting rod, and key lever, of a pair of intersecting levers pivotally connected to each other, one of the levers being pivotally connected to the key lever, a link pivotally connecting 5 the opposite lever to the type bar connecting rod, and a second link pivotally connecting the first link to the first mentioned lever and arranged to have a toggle action in connection with the first mentioned lever 10 when the type bar is actuated.

2. In mechanism for operating the type bar of a typewriting machine, the combination of a type bar and key lever, a bell crank pivotally connected to the key lever, a crank 20 member pivotally connected to said bell crank, a link pivotally secured to said last mentioned crank member and to the type bar connecting rod, in combination with a link pivotally connecting the bell crank and 25 said last mentioned link.

3. In a typewriting machine, the combination of a type bar, a key lever, a bell crank one member of which is pivotally secured to said key lever, a bell crank one 30 member of which is pivotally connected to said first mentioned crank at the junction of its members, a link, a connecting rod one end of which is connected to the type bar and the other end to said link, and a link 35 pivotally connected to said first mentioned link, and to the upper member of the first mentioned bell crank.

4. In mechanism for operating the type bar of a typewriting machine, the combination with a type bar, type bar connecting

rod and key lever, of a bell crank pivotally connected at one end thereof to the key lever, a second bell crank, having one end thereof pivotally connected to the middle portion of the first mentioned bell crank, a 45 link member pivotally connecting the opposite end of the second bell crank to the type bar connecting rod, and a second link member pivotally connecting the first link member to the opposite end of the first mentioned bell crank and arranged for coöperation with the first mentioned bell crank to produce a toggle action upon the first mentioned link member when the type bar is 50 actuated.

5. In mechanism for operating the type bar of a typewriting machine, the combination with a type bar, type bar connecting rod and key-lever, of a pair of intersecting bell crank levers one of which is pivotally 60 connected at one end to the other bell crank lever at the junction of the arms thereof, the second mentioned bell crank lever having one end thereof pivotally connected to the key-lever, a fixed pivot supporting the 65 first mentioned bell crank lever at the intersection of the two arms thereof, a link pivotally connecting the opposite end of one of the bell crank levers to the type bar connecting rod, and a second link pivotally 70 connecting the first link to the end of the other bell crank lever.

In testimony whereof, I have hereunto signed my name in the presence of two subscribing witnesses.

SYDNEY L. KAUFMAN.

In the presence of—

CLARENCE A. WILLIAMS,
JOHN H. RONEY.
